HANGER FOR IRONING TABLES

Lawrence J. Geluso, 5895 Ethelwin NE., Belmont, Mich.

Filed May 21, 1956, Ser. No. 586,301

4 Claims. (Cl. 211—86)

This invention relates to the construction of hanger racks for ironing tables. The important features of this invention are its detachable engagement with the edges of an ironing table, and its ability to maintain its position under load without the necessity of using clamps or other such coupling devices. Having eliminated the need for clamping mechanism, it becomes possible to form the complete unit from a single continuous length of ordinary steel rod. In one modification of the invention, the ends of the device are provided with jaw portions which grip the sides of the ironing table at opposite points, and are readily disengageable therefrom by deflecting the sides of the bracket. A modified form of the invention provides for a pivotal mounting of the ends of the unit to brackets on the under side of the ironing table, and involves the use of offset portions which serve as stops limiting the rotation of the bracket with respect to the ironing table. This unit can be collapsed into a position in which it lies substantially parallel to and adjacent the ironing table, and may be erected after the supporting legs of the ironing table have been unfolded. The position and formation of the offset portion are established so that the unit is swung upwardly about its pivot point to a position just "over center," so that any loading on the bracket tends to urge the bracket more securely against the stop formed by the offset portions. Preferably, the normally uppermost end of the bracket is formed as a connecting portion between the substantially parallel sides, and is provided with a reverse bend adjacent the junction of the end and sides to inhibit a tendency for hangers to slip off.

With this arrangement, the user of the ironing table may place ironed garments on hangers, and then suspend the hangers from the horizontal portion of the rack. After a considerable number of these has been accumulated, it is possible to detach the rack and its supported hangers bodily, and to carry them to a position for storage. If the hangers are all placed with the hook engaging the rod from the same direction, it is even possible to place the whole collection of hangers over a closet hang-rod with one movement, followed by withdrawal of the rack.

The several features of the invention will be analyzed in detail through a discussion of the particular embodiments illustrated in the accompanying drawing. In the drawing:

Figure 1 presents a perspective view of an ironing table equipped with a hanger rack embodying one form of the invention.

Figure 2 is an enlarged fragmentary view showing the engagement of the lower end of the hanger rack with the side of the ironing table.

Figure 3 is an enlarged fragmentary section of the plane 3—3 of Figure 2.

Figure 4 is a side elevation of a modified form of the invention.

Figure 5 is a perspective view of the pivot bracket

2

and lower end of the leg of the modification of the invention illustrated in Figure 4.

Referring to the drawing, an ironing table having the folding leg systems 11 and 12 and the top 13 is engaged by a hanger rack generally indicated at 14 supporting the hangers 15 and 16. The rack itself is preferably formed of a continuous piece of steel rod, and has the parallel sides 17 and 18 connected at the upper end by the normally horizontal portion 19. It is preferable that the juncture of the horizontal portion 19 with the sides 17 and 18 be formed with a reverse bend as indicated at 20 and 21, respectively, to inhibit any tendency for the hangers 15 and 16 to move out of engagement with the horizontal portion 19.

15 The free ends of the parallel sides 17 and 18 are provided with laterally offset portions as shown at 22 and 23, and the rod-stock of which the unit is formed is continued beyond these offset portions to form jaw portions as indicated at 24. Another jaw portion is formed as a 20 continuation of the offset portion 23 on the opposite side of the unit, which does not clearly appear in Figure 1. The jaw portion 24 is formed to receive the edge of the top 13, and is preferably provided with a section of tubular, resilient covering material 25 for engagement 25 with the under side of the table top. This arrangement makes it possible to disengage the rack 14 from the top 13 simply by deflecting the legs 17 and 18 away from each other at the lower ends; and, when engaged with the table top, the jaw portions 24 will maintain the unit 30 in an attitude slightly away from the vertical.

Referring to Figures 4 and 5, a modified form of the invention involves the provision of brackets 26 at opposite points on the under side of the ironing table for pivotally receiving the ends 27. An offset portion 28 extends in a direction transverse to the plane of the parallel sides 29 of this rack, and a second offset portion is formed preferably in the plane of the sides 29, and extending laterally with respect thereto outwardly to a point of junction with the sides 29. The sides 29 are spaced apart sufficiently to receive the width of the top 30 therebetween, and reference to Figure 4 will indicate that the rack can be rotated in a counter-clockwise direction to a point in which the legs approach parallelism with the table top 30, such movement being 45 limited by the engagement of a horizontal portion with the top surface. As with the other modification of the invention, it is preferable that the engagement of the ends 27 with the brackets 26 be disengageable to permit the bodily removal of the rack with its supported load.

The particular embodiments of the present invention which have been illustrated and discussed herein are for illustrative purposes only and are not to be considered as a limitation upon the scope of the appended claims.

55 In these claims, it is my intent to claim the entire invention disclosed herein, except as I am limited by the prior art.

I claim:

60 1. A hanger rack for an ironing table, comprising a member formed of flexible material and having two parallel sides of substantially equal length connected at the end by a portion perpendicular thereto, said sides being spaced apart sufficiently to receive the width of the top of said ironing table therebetween, the free ends of said sides each having a laterally-offset portion adapted to engage the underside of said ironing table, and a second offset portion extending away from the plane of said parallel sides; and means forming disengageable pivotal mounting at the end of said second offset portions 65 adapted to connect the same to the underside of said ironing table, said laterally offset portions being disposed 70

relative to the top of said hanger rack and to the axis of said pivotal mounting to position the top of said rack on the opposite side of a vertical plane through said axis from said laterally offset portion whereby the force of gravity will tend to maintain said rack in the erect position.

2. A hanger rack for an ironing table, comprising a member formed of flexible material and having two parallel sides of substantially equal length connected at one end by a portion perpendicular thereto, said sides being spaced apart sufficiently to receive the width of the top of said ironing table therebetween, the free ends of said sides each having a laterally-offset portion adapted to engage the underside of said ironing table with said rack in erected position, and a second offset portion extending away from the plane of said parallel sides; and means forming a pivotal mounting at the end of said second offset portion adapted to connect the same to the underside of said ironing table, said laterally offset portions being disposed relative to the top of said hanger rack and to the axis of said pivotal mounting to position the top of said rack on the opposite side of a vertical plane through said axis from said laterally offset portion whereby the force of gravity will tend to maintain said rack in the erect position.

3. A hanger rack for ironing tables, comprising a member formed of flexible material and having two parallel sides of substantially equal length connected at one end by a portion perpendicular thereto, said sides being spaced apart sufficiently to receive the width of the top of said ironing table therebetween, the free ends of said sides each having a laterally-offset portion adapted to engage the underside of said ironing table, and a sec-

ond offset portion extending away from the plane of said parallel sides; and means forming a disengageable pivotal mounting at the end of said second offset portion adapted to connect the same to the underside of said ironing table.

4. A hanger rack for ironing tables, comprising a member formed of flexible material and having two parallel sides of substantially equal length connected at one end by a portion perpendicular thereto, said sides being spaced apart sufficiently to receive the width of the top of said ironing table therebetween, the free ends of said sides each having a laterally-offset portion adapted to engage the underside of said ironing table, and a second offset portion extending away from the plane of said parallel sides; and means forming a pivotal mounting at the end of said second offset portion adapted to connect the same to the underside of said ironing table.
